[57] CLAIM

The ornamental design for a concave shaped cooking lid with ergonomic handle, as shown and described.

DESCRIPTION

FIG. 1 is a perspective view of a concave shaped cooking lid with ergonomic handle showing my new design;

FIG. 2 is a top view of the new design of the concave shaped cooking lid with ergonomic handle;

FIG. 3 is a bottom view of the new design of the concave shaped cooking lid with ergonomic handle; and,

FIG. 4 is a side view thereof, all other side views being identical.

FIGS. 2 and 3 are drawn on a reduced scale.
